Primary Examiner — Kevin Rudzinski**CLAIM**

The ornamental design for a solar-powered light, as shown and described.

DESCRIPTION

FIG. 1 is a perspective view of a solar-powered light in accordance with the present invention;

FIG. 2 is a first side view of the solar-powered light shown in FIG. 1. The opposing side is identical/symmetrical with FIG. 2;

FIG. 3 is a second side view of the solar-powered light shown in FIG. 1. The opposing side is identical/symmetrical with FIG. 3;

FIG. 4 is an enlarged top view of the solar-powered light shown in FIG. 1; and,

FIG. 5 is an enlarged bottom view of the solar-powered light shown in FIG. 1.

The broken lines shown in the drawings illustrate unclaimed portions of the solar-powered light and environmental structures and form no part of the claimed design.
